UNITED STATES PATENT OFFICE

HENRY C. THOMAS, OF TORONTO, ONTARIO, CANADA

APPARATUS FOR FORMING A DECKEL EDGE UPON PAPER SHEETS, CARDS, OR THE LIKE

Application filed November 7, 1928. Serial No. 317,836.

It is customary to form on paper sheets, cards or the like a deckel edge in imitation of the regular deckel which occurs in the manufacture of paper. This imitation deckel has usually been done manually, the workman using a file or other tool to scratch or mark the edge of the sheet. This is a comparatively slow and expensive method, and the object of my invention is to devise apparatus by means of which paper sheets or cards may be provided with a deckel edge much more rapidly than by the hand process, and which will result in a superior finished article.

I attain my object by providing on a rotary shaft a head carrying one or more series of cutters, the working face of the head being formed as a very flat cone, the inclination of the sides of the cone being preferably just sufficient to allow the cutters to pass the work on its upward movement without engaging the work.

The apparatus is constructed in detail substantially as hereinafter described and illustrated in the accompanying drawings in which

Fig. 1 is a side elevation of my improved apparatus;

Fig. 2 a plan view of part of the same;

Fig. 3 a rear view of the cutter head;

Fig. 4 a similar view of a modified form of cutter head;

Fig. 5 a section through a part of the cutter head; and

Fig. 6 a sectional detail illustrating the construction of the work support.

In the drawings like numerals of reference indicate corresponding parts in the different figures.

1 is a supporting frame, which may be of any suitable construction and is provided at its upper part with bearings 2 for the shaft 3. This shaft is provided at one end with a suitable pulley 4 by means of which it may be driven and at its other end is mounted the cutter head 5.

This cutter head 5 is the important feature of my invention and comprises a metal disk having its working face formed as a very flat cone. The head is provided on its back with one or more ribs 7, and through the ribbed

portions are formed holes to receive the cutters 6. Set screws 8 are threaded through the sides of the ribs to engage the cutters and lock them in position. By unscrewing the set screws, the cutters may be arranged to project beyond the face of the head as desired.

The cutters may be arranged in any desired manner on the head. I prefer, however, to employ two series, which may be arranged in straight radial lines as shown in Fig. 4, or may be arranged on curved lines as shown in Fig. 3. The latter, however, is preferable for the reason that when the cutters are arranged as shown in Fig. 4, they engage the work substantially simultaneously and there is therefore a considerable jar on the machine, whereas, when the cutters are arranged as shown in Fig. 3 there is a wider time gap between the engagement of the individual cutters with the work and therefore the jar on the work and machine is considerably reduced. It will be evident, of course, that other arrangements than that shown in Fig. 3 may be devised to cause the cutters to engage the work one after the other.

The work 9 is supported on a platform, which is preferably, although not necessarily, movable to and from the working face of the head. The edge of the platform is arranged parallel to the downwardly moving side of the conical face of the head, and the inclination of the sides of the working face need only be sufficient for the cutters to clear the platform on their upward movement at the opposite side.

It is important, of course, that the work be rigidly supported adjacent the cutter head. The platform, will in the main be of metal, but I prefer to provide it with a facing of wood, or other comparatively soft material, and it might even be made of brass, copper, or other soft metal not likely to injure the cutters. With this arrangement the platform may practically touch the working face of the head and the cutters will themselves form their own grooves in the facing, the facing between the grooves providing support for the work. In Fig. 6 the method of applying the facing is shown. To the forward edge of the platform 10 is secured by screws 11 a bar

12, which strip extends both in front of and below the platform, and is supported by a metal bar 13. The bar 12 of softer material is preferably formed with a separate facing 12^a, which may be glued to the main bar 12. 5 When therefore through continued use the facing 12^a becomes badly worn or damaged, it is quite a simple matter to replace it. The main advantage, however, is that the work 10 may be supported quite close to the disk without the necessity of having to go to the trouble of providing special grooves for the passage of the cutters.

The platform is arranged to move to and 15 from the working face of the head, being slidably mounted on guides 24. To actuate the platform I fulcrum on the frame 1 the bell-crank lever 14 which with one end engages the under side of the platform, and its 20 other end is connected by a link 15 to a foot-operated lever 16. These parts are for the purpose of moving the platform towards the head, while springs 17 mounted on the guides 24 are for the purpose of moving the platform 25 away from the head.

On the top of the platform I provide a 30 guide for the rear of the stack of work, which guide is formed as an angle bar 18 having a pair of short slots 19 in each end of its horizontal leg.

Adjacent each side of the platform is a double row of holes 20, the holes in one row being arranged in staggered relationship to those in the other row. Bolts 21 are provided for 35 securing the angle bar in any desired position.

I preferably thread through the vertical leg of the angle bar 18 and in these holes are threaded screws 22, on the ends of which is 40 carried a guide 23. A very fine adjustment is therefore possible without materially weakening the supporting platform.

The device is operated as follows. The 45 stack of work is positioned on the platform and the head is caused to rotate. The platform is held in advanced position during cutting and then allowed to move away, the work then moved to a fresh position and the platform again advanced. The platform is 50 advanced and retracted and the work moved until the edge of the work has been sufficiently cut to produce the desired effect.

In actual practice, usually three or four 55 moves of the stack will be sufficient, but this will naturally depend largely on the length of the work.

From the above description it will be seen 60 that I have devised a construction which will satisfactorily attain the object of my invention as set out in the preamble of this specification.

What I claim is:

1. In apparatus for the purpose described, 65 a rotary cutter head, its working face being

formed as a flat cone having a cutting projection on said working face.

2. In apparatus for the purpose described, 70 a rotary cutter head, its working face being formed as a flat cone having a series of cutting projections on said working face.

3. In apparatus for the purpose described, 75 a rotary cutter head, its working face being formed as a flat cone having a plurality of series of cutting projections on said working face.

4. In apparatus for the purpose described, 80 a rotary cutter head, its working face being formed as a flat cone having a series of cutting projections on said working face, said projections being arranged in a curved row.

5. In apparatus for the purpose described, 85 a rotary cutter head, its working face being formed as a flat cone having a plurality of series of cutting projections on said working face, the projections in each series being arranged in a curved row.

6. In apparatus for the purpose described, 90 a rotary cutter head having its working face formed as a flat cone and a rib on its back, said cutter head having a hole formed through said working face and rib; a cutter in said hole; and a set screw threaded through the rib and adapted to engage the cutter.

7. In apparatus for the purpose described, 95 the combination of a supporting frame; a cutter head rotatable on said frame, on a horizontal axis, the working face of said head being formed as a flat cone having a cutting projection on said working face; and a work support having its edge paralleling the downwardly moving side of said working face.

8. In apparatus for the purpose described, 100 the combination of a supporting frame; a cutter head rotatable on said frame on a horizontal axis, the working face of said head being formed as a flat cone having a cutting projection on said working face; and a work support having its edge paralleling the downwardly moving side of said working face, said support having its edge adjacent the head formed of a material softer than the projection.

9. In apparatus for the purpose described, 105 the combination of a supporting frame; a cutter head rotatable on said frame on a horizontal axis, the working face of said head being formed as a flat cone having a cutting projection on said working face; and a work support having its edge paralleling the downwardly moving side of said working face, said support having its side adjacent the head formed with a removable portion 110 of a material softer than the projection.

10. In apparatus for the purpose described, 115 a rotary cutter head, its working face being formed as a flat cone having a series of cutting projections on said work- 120

ing face, said projections being arranged in other than a line radially of said head.

11. In apparatus for the purpose described, a rotary cutter head, its working face being formed as a flat cone having a series of cutting projections on said working face, said projections being arranged to engage the work one after the other.

Signed at Toronto, Canada, this 29th day
10 of October 1928.
